JOHN HARRIS, OF CLEVELAND, OHIO, ASSIGNOR, BY MESNE ASSIGNMENTS,
TO SAMUEL H. SMART, OF WILLOUGHBY, OHIO.

GAS-BURNER.

SPECIFICATION forming part of Letters Patent No. 742,642, dated October 27, 1903.
Application filed September 30, 1901. Serial No. 77,035. (No model.)

To all whom it may concern:

Be it known that I, JOHN HARRIS, a resident of Cleveland, in the county of Cuyahoga and State of Ohio, have invented certain new and useful Improvements in Gas-Burners; and I hereby declare the following to be a full, clear, and exact description of the invention, such as will enable others skilled in the art to which it pertains to make and use the same.

10 This invention relates to improvements in gas-burners designed more especially for use in burning acetylene gas or other gases which are rich in carbon.

The object of this invention is to provide a burner which has a large illuminating capacity, which is especially adapted for successfully burning acetylene gas with a mantle or other body capable of being rendered incandescent by exposure to the flames issuing from the burner, which is so constructed that it will successfully operate with a low pressure of gas in the gas-supply pipe, which is noiseless in its operation, which avoids the ingress or backing up of the flame into the burner during the operation of the burner, which is capable of successfully operating in atmospheres varying in density, and which is not affected in the performance of its work by drafts or currents of air through the room or space illuminated by the burner.

30 With this object in view and to the end of realizing other advantages hereinafter appearing the invention consists in certain features of construction and combination of parts hereinafter described, and pointed out in the claims.

In the accompanying drawings, Figure I is a side elevation, in central vertical section, of the burner provided with mantle and chimney. Fig. II is an enlarged top plan in horizontal section on line II II, Fig. I. Fig. III is an enlarged vertical section of the upper portion of the burner on line III III, Fig. I. Fig. IV is an enlarged top plan in horizontal section on line IV IV, Fig. I.

45 The burner comprises an upright gas-receiving metal tube *a*, which forms the lower end of the device. The tube *a* has its lower portion screw-threaded internally to render it capable of being screwed onto a gas-supply pipe. (Not shown.) The tube *a* is formed

at its upper end and centrally into a nose or nozzle *b*, which is preferably conical externally and arranged to discharge the gas supplied to the tube *a* vertically and upwardly. 55 The tube *a* is provided at the lower or inner end of its nose or nozzle *b* with an external annular flange *6*.

An endwise shiftable or adjustable vertically-arranged tube *c* is arranged in line with the nose or nozzle *b*. Preferably the tube *c* is screw-threaded externally and engages corresponding screw-threads formed internally of the lower end of a stationary vertically-arranged tube *d*, which is preferably provided 65 at its lower end and externally with laterally and outwardly projecting arms or members 7, arranged at suitable intervals around the said tube *d* and riveted to or otherwise rendered rigid with two standards 8 and 8, which 70 project vertically upwardly from and are integral or rigid with the flange 6 of the tube *a* at opposite sides, respectively, of and equidistant from the nose or nozzle *b*.

The tube *d* is provided at or near the upper end of the tube *c* with a mixing-chamber *e*, centrally of which is placed a vertically-arranged perforated hollow drum *f*, which is preferably cylindrical and gradually enlarged toward the upper end and rendered stationary by forcing it into and causing it to tightly engage the tube *d* around the upper end of the tube *c* or in any other approved manner. The drum *f* is open at its lower end and communicates interiorly with the tube *c*, which 85 discharges upwardly into the drum. The sides and the top of the drum have numerous perforations 10. The casing of the mixing-chamber *e* is preferably cylindrical and integral or rigid with the tube *d* and is of 90 course considerably larger transversely than the said tube.

The chamber *e* is provided at its upper end with a head *g*, which is preferably circular and seated upon an upwardly and inwardly facing annular shoulder 12, formed upon the upper end of the casing of the said chamber. The head *g* is provided at its under side and centrally with a depending lug 13, which has a vertically-arranged screw-threaded hole 14, 95 engaged by the correspondingly-threaded shank of a screw *h*, which extends through

the top of the drum *f* and has its head abutting against the under side of the said top. The screw *h* consequently holds the head *g* down upon the drum *f*. An annular space *k* is formed, therefore, around the lug *l*, which chamber is in open relation around the upper end of the drum *f* with the space between the drum and the surrounding wall or walls of the mixing-chamber *e*.

- 10 The head *g* is provided with four upwardly-discharging and upwardly-projecting tubular projections or nozzles *l*, having the passage-ways therethrough preferably round and in open relation with the space *k*. The projections or nozzles *l* are arranged, preferably, equidistant apart around and equidistant from the center of the head *g*.

The drum *f* is large enough at its upper end to extend in under the whole of all of the 20 passage-ways extending through the projections or nozzles *l*, and preferably a washer *m*, of fireproof material—such, for instance, as asbestos—is interposed between the head of the screw *h* and the under or inner side of 25 the top of the drum *f*.

The tube *c* extends a suitable distance below the tube *d*, as already indicated, and has its lower end enlarged transversely, as at 15, and surrounding the gas-discharging nose or 30 nozzle *b*. The external annular shoulder 16, formed at the upper end of the lower enlarged portion 15 of the tube *c*, is perforated, preferably, so as to form several air-inlets 17, arranged at equal intervals around the said tube and discharging downwardly into the 35 said portion 15 of the tube.

A chimney-holder *r* surrounds the tube *d* externally of the standards 8 and is provided at its lower end with inwardly-projecting 40 arms 18, which are riveted or otherwise secured to the said standards, and suitably-applied braces *t* extend between the lower end of the casing of the chamber *e* and the lower end of the chimney-holder. A globe, glass, 45 or chimney *u* is shown within the chimney-holder and surrounds the burner in the usual manner.

The chimney-holder *r* bears a mantle-holder *x*, which is usually a rod or wire extending 50 upwardly into the chimney, and the mantle *y*, which is to be rendered incandescent, is suspended from the upper end of the mantle-holder and has its lower end embracing the upper end of the casing of the chamber *e*.

55 In the operation of the burner the air which supplies the oxygen necessary to produce proper combustion passes into the lower end of the tube *c*, and the gas is discharged by the nozzle *b* into the said end of the tube *a*, and 60 the gas is discharged by the nose or nozzle *b* into the lower end of the tube *c*. The air which enters the tube *c* is largely supplied through the air-inlets 17, and generally air also enters the said tube at its lower end. The 65 air and the gas pass upwardly through and commingle more or less within the tube *c* and are discharged by the latter upwardly into the

drum *f*, wherein the gas and the air more thoroughly commingle, and the resulting combustible and inflammable mixture passes 70 from within the drum through the numerous perforations in the top and sides of the drum into the space surrounding the drum and into the annular space *k* next above the drum; but all of the mixture discharged from the 75 drum finds its way into the space *k* and is uniformly distributed by the latter to the tubular projections or nozzles *l*, at the outer ends of which the mixture upon ignition burns with perfect combustion. It will be observed 80 also that the upward enlargement of the drum results in a compression of the mixture passing upwardly externally of the drum.

The endwise adjustability of the tube *c* enables the regulation of the distance between 85 the air-inlets 17 and the gas-discharging nose or nozzle *b* and also the opening at the lower end of said tube around the said nose or nozzle, and it has been found that the volume of air supplied in advance of the gas-supply 90 nozzle must be decreased or increased in order to obtain perfect combustion, according as the density of the atmosphere increases or decreases. The velocity of the flow of gas into the tube *c* is retarded by an increase in 95 the density or supply of air in advance of the gas-supply orifice or passage-way. The importance therefore of the endwise adjustability of the tube *c* is obvious. Hence it will be observed that the tube *c* after it has been adjusted as required for an atmosphere of given density is shifted endwise in the required direction by properly manipulating the said tube when the atmosphere changes in density, and the required proportions of air and 105 gas to produce the desired combustion are readily obtainable by properly adjusting the tube *c* upon lighting the burner and observing the character of the flame issuing from the burner.

A bluish or a whitish flame can be produced at pleasure, and the arrangement of the parts are such that the air-supply cannot be reduced to such an extent as to result in the production of a flame that is not smokeless. 115 In other words, the arrangement of parts is such that when the tube *c* is shifted into its lowermost position against the tube *a* enough air will still be supplied through the air-inlets 17, and the proportions of air and gas will not 120 be affected to such an extent as to result in a smoky flame during the operation of the burner. It will be observed also that as the gas-supply nozzle is surrounded by the tube *c* and the air-receiving openings of the said tube 125 are arranged above and below the discharging end of the said nozzle a draft or current of air straight across the interior of the said tube at the said end of the said nozzle is rendered impossible. The lower enlarged portion 15 of the tube *c* forms, therefore, not only 130 the receiving end of the said tube, but constitutes a guard which prevents the creation of such a draft or current without interfering

with the provision of the desired air-inlets at the ends of the guard. It will be observed also that the perforated top of the drum ⁵ constitutes a screen arranged next below the space *k* and preventing backing up of the flames into the burner during the operation of the burner.

What I claim is—

1. A gas-burner having its upper and flame-feeding end comprising a head constructed to discharge upwardly; a mixing-chamber wherein the component parts of the inflammable mixture commingle, which chamber is arranged under the aforesaid head and in open relation with the outlet of the burner; a vertical commingling-tube arranged to discharge upwardly into the said mixing-chamber, and a gas-supply tube arranged to discharge vertically upwardly and centrally of the said commingling-tube, and the receiving end of the commingling-tube forming a vertically-arranged guard surrounding the discharging end of the gas-supply tube, which guard is larger diametrically than the remaining portion of the commingling-tube and communicates at both ends with the external atmosphere.

2. A gas-burner having the following: a mixing-chamber; a head extending over the said chamber and provided centrally with a depending lug and having several upwardly-discharging ports or passage-ways arranged at suitable intervals around the center of the head and in open relation with the space around the aforesaid lug; a screen arranged transversely of the mixing-chamber at the lower end of and secured to the aforesaid lug and extending in under the aforesaid ports or passage-ways; and means for conducting the component elements of the inflammable mixture to the mixing-chamber below the screen, substantially as and for the purpose set forth.

3. A gas-burner having the following: a mixing-chamber; a head extending over the said chamber and provided centrally with a depending lug having a screw-threaded hole, which head has, also, upwardly-discharging ports or passage-ways spaced at suitable intervals around the center of the head and in open relation with the space around the aforesaid lug; a screen arranged transversely of the mixing-chamber at the lower end of the aforesaid lug and extending in under the aforesaid ports or passage-ways; a screw extending centrally through the screen and engaging the aforesaid threaded hole and holding the screen against the lower end of the aforesaid lug, and means for conducting the component elements of the inflammable mixture to the mixing-chamber below the screen, substantially as and for the purpose set forth.

4. A gas-burner having the following: a mixing-chamber; a head extending over the said chamber and provided with an upwardly-discharging port or passage-way extending through the head; a hollow drum arranged

centrally of the aforesaid chamber and having the side and top walls of its chamber provided with numerous perforations, which drum has its perforated top arranged a short distance below and extending in under the aforesaid port or passage-way, and means for conducting the component elements of the inflammable mixture to the chamber of the drum, and the space between the head and the top of the drum being in open relation with the space surrounding the drum.

5. A gas-burner having the following: a mixing-chamber; a head extending over the said chamber and having upwardly-discharging ports or passage-ways; a hollow drum arranged centrally of the aforesaid chamber and having the side and top walls of its chamber provided with numerous perforations; a space or passage-way formed between the head and the top of the drum and connecting with the aforesaid upwardly-discharging ports or passage-ways and in open relation around the said top with the space surrounding the drum, and means for conducting the component elements of the inflammable mixture to the chamber of the drum, substantially as and for the purpose set forth.

6. A gas-burner having the following: a mixing-chamber; a head seated upon the upper end of the casing of the mixing-chamber and provided centrally with a depending lug having nozzles spaced equidistantly around and from the center of the said head; a perforated hollow drum arranged centrally of the mixing-chamber and having its top secured against the lower end of the aforesaid lug, and means for supplying the component elements of the inflammable mixture to the mixing-chamber, and the space around the aforesaid lug and above the drum being in open relation with the space around the drum and communicating with the inner ends of the nozzles.

7. A gas-burner having its flame-feeding end constructed to discharge upwardly; a mixing-chamber wherein the component parts of the inflammable mixture commingle, which chamber is in open relation with the flame-feeding outlet of the burner; an endwise-shiftable commingling-tube arranged to discharge into the mixing-chamber and having its receiving end enlarged transversely and being in open relation, at both ends of its said enlarged portion, with the external atmosphere, and a gas-supply tube arranged to discharge into the said enlarged portion of the commingling-tube.

8. A gas-burner comprising the following: a gas-supply tube having a discharging- orifice; an endwise-adjustable commingling-tube enlarged diametrically at its receiving end in open relation with the external atmosphere and having its enlarged and receiving portion surrounding the discharging end of the gas-supply tube; a mixing-chamber arranged at the discharging end of the commingling-tube; upwardly-discharging nozzles

arranged above the mixing-chamber; a hollow perforated drum arranged within and centrally of the mixing-chamber and in open relation interiorly with the commingling-tube, 5 and the space within the casing of the mixing-chamber externally of the drum being in open relation with the aforesaid nozzles.

9. A gas-burner comprising the following: a vertically-arranged gas-supply tube provided at its upper end and centrally with a vertically-arranged cone having an upwardly-discharging orifice; a vertically-adjustable commingling tube enlarged diametrically at its lower and receiving end and having its enlarged receiving portion surrounding the upper portion of the aforesaid cone and provided with air-inlets; an outer tube surrounding the upper portion of the aforesaid commingling-tube and supported from the gas-supply tube and having its upper portion enlarged diametrically to form a mixing-chamber; a head arranged over the mixing-chamber and having upwardly-discharging nozzles, and a hollow perforated drum arranged 25 within and centrally of the mixing-chamber and inserted within the aforesaid outer tube around the commingling-tube, which drum is in open relation interiorly with the commingling-tube.
10. A gas-burner comprising the following: a vertically-arranged gas-supply tube provided at its upper end and centrally with a

vertically-arranged upwardly-discharging orifice, which tube has, also, an external annular flange; two standards arranged at opposite sides, respectively, of and rigid with the said flange; a vertically-adjustable commingling-tube enlarged diametrically at its lower and receiving end and having its said enlarged receiving portion surrounding the discharging end of the gas-supply tube and provided at its upper end with air-inlets; an outer tube surrounding the upper portion of the commingling-tube and rigid with the aforesaid standards; a mixing-chamber formed at 45 the upper end of the said outer tube and in open relation with the commingling-tube; a head extending over the said chamber and having upwardly-discharging ports or passage-ways equidistantly spaced around the center of the head; a screen at the inner side of the head and extending in under the last-mentioned ports or passage-ways, and an annular space between the screen and the head and communicating with the said ports or passage-ways, substantially as and for the purpose set forth.

Signed by me at Cleveland, Ohio, this 18th day of September, 1901.

JOHN HARRIS.
